UNITED STATES PATENT OFFICE.

SANDER LANKHEET, OF HAMILTON, MICHIGAN.

ELEVATOR.

Application filed September 18, 1920. Serial No. 411,031.

To all whom it may concern:

Be it known that I, SANDER LANKHEET, a citizen of the United States, residing at Hamilton, in the county of Allegan and 5 State of Michigan, have invented new and useful Improvements in Elevators, of which the following is a specification.

This invention relates to an elevator and has for its primary object the construction of 10 an elevator that will more effectively grip material or articles and will automatically release the same when reaching the delivery point.

An object of the invention is to provide a 15 simple, light, portable, durable machine that may quickly elevate grain bundles on stacks or in barns.

Another object of the invention is to accomplish these forgoing results in a very 20 efficient, automatic manner.

A feature of the invention is the novel manner of constructing and associating the hooks with the chain and the movable frame so that the elevating action of the elevator 25 may be changed without in any way interfering with the automatic opening and closing of the hooks.

With these and other objects in view the invention will be better understood from the 30 following detailed description taken in connection with the accompanying drawing wherein:

Fig. 1 is a side elevation of the elevator.

Fig. 2 is a detailed plan view of a portion 35 of the elevator.

Fig. 3 is an enlarged view showing the hook in loading position.

Figs. 4 and 5 are detailed views of the 40 clip.

Figs. 6 and 7 are detailed views of the pivot construction.

Again referring to the drawing illustrating one of the many constructions of my invention the numeral 1 designates a frame 45 mounted for swinging movement about the shaft 2 so that the upper end may be raised and lowered in the arc of a circle. The frame 1 includes a platform 3 of a construction and extending in a direction to have 50 flat engagement with the upwardly traveling portion 4 of a chain 5. This chain 5 passes around an upper sprocket wheel 6 rotatably supported by the frame, and lower sprocket wheel 7 mounted on the shaft 2. 55 The shaft 2 has a drive sprocket wheel 8 secured thereto which is engaged by the drive

chain 9 driven in any suitable manner. A vertical stationary frame 10 supports the heretofore mentioned parts for their movement. Arranged adjacent the lower end of 60 the frame, which is the loading end, is a table 11 inclined so that the material or bundles arranged thereon will move towards the chain. Mounted upon the chain at spaced points are the hooks 12, each of a 65 novel construction now to be described. Certain links 13 of the chain have ears 14 provided with holes 15 for a purpose hereinafter described. The numeral 16 designates a sleeve bolted to the ears 14 of one of the 70 links and receives the pin 17. The ears of the next adjacent link are bolted to the block 18 to which is secured a clip 19 that is provided with spaced holes 20. The numerals 21 and 22 designate the companion 75 members of the hook. In this particular instance each member is constructed from a length of wire bent to provide a gripping limb 23, a supporting limb 24 and a coiled portion 25 that is mounted on the pin for pivotal movement but held against displacement by the cotter pin 26. From this construction it will be seen that when the free end of the 80 supporting limbs are passed through the holes 20 the companion members will be thrown about the pin 17 when the chain is making a turn so as to space the gripping limbs 23 at an inclination to the chain so that material or bundles will be effectively 85 arranged upon the hook at the loading end 90 of the platform, gripped in its travel over the platform and mechanically released at the unloading upper end of the platform.

To complete the invention I provide an 95 adjustable support 27 for holding the frame at any inclination necessary to deposit the bundles or material at the point of delivery.

From the foregoing description taken in connection with the accompanying drawing it will be apparent that I provide an elevator 100 of simple, inexpensive construction, and which, besides supporting the bundles or articles, will exert pressure thereon in the traveling of the bundle which is a great advantage when elevating bundles of straw. 105 or grain.

It is, of course, to be understood that the invention may be constructed in various other manners and the parts associated in different relations and therefore, I do not 110 desire to be limited in any manner except as set forth in the claims hereunto appended.

Having thus described my invention what I claim is:

1. In an elevator construction, a traveling chain, rotary sprockets for moving said chain, hooks pivotally connected to the chain at spaced points, and clips secured to the chain at spaced points, said clips adapted to engage the adjacent hook during travel of the clips about the sprockets for moving the hooks into loading and unloading positions.

2. In an elevator construction, a traveling chain, rotary sprockets for moving said chain, hooks pivotally connected to the chain at spaced intervals, said hooks comprising gripping limbs and supporting limbs, clips secured to said chain at spaced intervals and engaging the supporting limbs of the hooks adjacent thereto whereby the gripping limbs of the hooks will be forced away from the chain into loading and unloading positions during travel of the clips about the sprockets.

3. In combination with a traveling chain,

a pivot pin secured to one of the links thereof, a clip secured to another spaced link of 25 the chain and provided with a pair of openings, and a pair of wire members, each having a gripping limb, and a supporting limb having its free end mounted in one of the holes of the clip, said member being looped 30 at the point of juncture of the gripping limb with the supporting limb and mounted on said pin.

4. In an elevator construction, a traveling chain, rotary sprockets for moving said 35 chain, pivot pins secured to certain of the links of said chain, clips carried by other of the links of said chain, and provided with a pair of openings, and article gripping hooks pivotally mounted upon said pivot 40 pins, said clips provided with openings for receiving portions of said gripping hooks therethrough.

In testimony whereof I affix my signature.

SANDER LANKHEET.
